WINDOW CONSTRUCTION

Roy T. Axe, Syracuse, N. Y., assignor to The O. M. Edwards Company Inc., Syracuse, N. Y., a corporation of New York

Application July 1, 1936, Serial No. 88,441

11 Claims. (Cl. 189—64)

This invention relates to window structures, particularly for railway cars, buses, and the like, and has for its object a window frame construction by which the frame is readily mounted in the 5 window opening and secured therein without fastening members or screws exposed on the inner or outer sides of the frame or the body in which the frame is mounted.

It further has for its object a means herein- 10 after pointed out for securing the frame of the window opening without exposed fastening members.

It further has for its object a window frame with rounding corners and slideable sash therein 15 with rounding corners, the frame and the sash interfitting at the margins of the sash, and means by which the sash can be demounted from the frame by sliding the sash out of the rounding corners onto a removable section of the frame into 20 a position, whereby the sash and the removable section of the frame can be demounted or replaced as a unit.

It further has for its object a frame including 25 a demountable section along one rail thereof, particularly between the rounding corners.

The invention consists in the novel features and 30 in the combinations and constructions hereinafter set forth and claimed.

In describing this invention, reference is had 35 to the accompanying drawings in which like characters designate corresponding parts in all the views.

Figure 1 is a side elevation of a window structure embodying my invention, contiguous portion 40 of the structural body in which the window is mounted being also shown.

Figure 2 is a sectional view on line 2—2, Figure 1.

Figure 3 is an enlarged sectional view on line 45 3—3, Figure 1.

Figure 4 is an enlarged fragmentary isometric view of the window frame, the removable portion being shown as demounted.

The car body or structural body provided with 50 a window opening may be of any suitable form, size and construction. It includes generally upper and lower rails 1, 2, posts 3 and outer and inner facing sheets 4, 5. The rails 1, 2 and posts 3 are, in the illustrated embodiment of my invention, formed hollow and of metal, the posts 3 meeting the rails 1, 2 at a right angle. The sheeting 4, 5 is suitably secured to the frame members or rails and posts 1, 3 and is in the 55 illustrated embodiment of the invention shown as formed with webs 6 at the corners of the window opening.

1 designates generally the window frame, this being here illustrated as rectangular in general form with rounding corners, the frame being in 60 the form of an inwardly facing channel with its

bottom 8 toward the inner faces of the posts 3 and rails 1, 2.

9 and 10 designate the outer and inner side flanges of the channel. The frame is also formed with an external circumferential flange 11 on the 5 outer side thereof, which laps the car body around the window opening or laps the margin of the sheeting 4. A suitable gasket 12 is interposed between the flange and the margin of the sheeting 4. The frame is usually formed of extruded 10 metal and bent into rectangular form with rounding corners. The frame may be of one piece or a plurality of pieces welded together. It is preferably of two pieces, one of which extends along the bottom rail 2 and includes a removable 15 section between the lower rounding corners, as will be hereinafter explained. The bottom 8 of the frame 7 constitutes a portion which telescopes into the window opening and a circumferential flange 11 forms a facing for the margin 20 of one lateral side wall of the car body around the window opening.

14 and 15 designate sashes slidably mounted in the frame.

In the window here shown, these sashes are 25 shown as slideable horizontally in the frame, and when entirely closed, the outer stile 16 of one sash laps the corresponding stile 17 of the other sash midway between the ends of the frame, as seen in Figure 2. The sashes 14, 15 are also here 30 illustrated as provided with rounding corners for conforming respectively with the rounding corners at the opposite ends of the frame 7. The frame 7 and the sash are formed with interfitting parts, as ribs and grooves, the frame 7 being 35 formed with ribs 18 and 19 which also extend around the rounding corners from the bottom 8 of the channel. The sash, as best seen in Figure 3, are formed with grooves 20 for receiving the rib 18 or 19, the rib 18 entering the groove of 40 the sash 14 and the rib 19 coacting with the groove of the sash 15, and the grooves or channels of the sash being provided with a fibrous U-shaped lining 21 for receiving the rib and holding the sash and the frame from out of metal-to-metal 45 contact.

The frame is held in the window opening by fastening members exposed or accessible from the bottom 8 of the channel of the window frame 7, so that no fastening members or screw heads 50 are exposed on the inner and outer sides of the window structure.

The frame is located in the window opening by the flange 11 coacting with one face, as the outer face, of the car or structural body and is held in 55 this position by the fastening members or screws to be presently described and an additional retaining member 22 having a leg or strip portion 23 extending between the bottom 8 of the channel and the inner face of the contiguous post 3 and 60

having a head 24 having flanges lapping the outer face of the side flange 10 of the channel of the frame 7 and the outer face of the sheeting 5. The fastening members or screws 25 extend 5 through the bottom 8 of the channel, the leg 23 and into the post 3, the heads of the screws being exposed on the bottom 8 of the channel. The leg or strip 23 of the member 22 constitutes a portion telescoping into the window opening and 10 lapping the telescoping portion or the bottom 8 of the frame member 7, and the head 24 of the member 22 serves as a flange lapping the margin of the lateral side wall of the car body around the window opening, opposite to the side lapped by 15 the flange 11 of the frame member 7 and forms a facing therefor. The fastening screws extend through the lapping portions. Thus, the parts are assembled by telescoping the members 7 and 22 into the window opening and finally fastening 20 them together with the fastening screws. Usually, in assembling, the telescoping portion or bottom 8 of the frame member 7 is formed with screw holes and when the two members 7 and 22 are brought into proper position, the holes in the 25 lapping portion or strip 23 of the member 22 are marked through the holes in the bottom 8 and then bored out for receiving the screws.

The member 22 may be in the form of a rectangular frame with rounding corners or may 30 be made up of sections. It is preferably a single unit in the form of a rectangular frame.

The frame 7 and the retaining member 22 constitute sections of a complete window frame, the bodies of which telescope, one in the other, 35 within the window opening, which sections are insertable in the window opening from opposite sides of the opening with the bodies or telescoping portions lying flatwise, one on the other, and secured together by screws passing through them. 40 The bottom rail of the window includes a removable section 26 located between the rounding corners. This section 26 is angular in cross section and formed with an external flange 11^a forming a continuation of the flange 11 and also 45 with ribs 19^a and 18^a forming continuations of the ribs 19, 18. The ribs 19^a, 18^a extend into the grooves in the lower rails of the sashes. The section 26 overlies a base strip 27 angular in cross section and having a flange 28 along its outer 50 edge alined with the flange 10. The base strip extends under the bottom of the channel at the rounding corners and is secured to the bottom of the channel, as by welding. The abutting ends of the flanges 10 are also welded together. The 55 leg 23 of the retaining member 22 extends between the removable section 26 and the base strip 27. The section 26 is secured in position by screws 29 extending therethrough through openings 30 in the strip 27 and through the interposed leg 23 and into the body structure. The 60 gasket 12 extends between the flanges 11^a and the sheeting 4 over the bottom rail 2.

In operation, the sashes are moved to lap each other sufficiently so that their over-all length is 65 less than that of the removable section 26. The removable section 27 placed with the ribs 19^a, 18^a in the grooves of the bottom rails of the sashes 14, 15. Then while the sash is tilted, the grooves on the upper rail thereof are interfitted with the 70 portions of the ribs 19, 18 on the upper rail of the frame. Then the sash with the removable strip 26 swung inwardly, as a unit, between ribs 19^a, 18^a into alinement with the ribs 18, 19 and the screws 29 applied. To remove the sash, the 75 reverse of this movement takes place.

By this construction, a rectangular sash with rounding corners is provided which interfits throughout the circumference of the sash leaving no cracks or crevices and also the sash can be readily demounted for re-glazing or for repairing. Furthermore, the frame construction consists of a few parts, as the channel 7, removable section 26, retaining member 22 and the screws, which screws are hidden or not exposed.

What I claim is:—

1. In a window construction, the combination with a body formed with a rectangular window opening, of a rectangular frame mounted in the opening and formed with rounding corners, the frame being channel-shaped in cross section with 15 the channel facing inwardly and with a circumferential external flange lapping the body around the window opening at one side of the frame, sashes slidably mounted in the frame and having 20 rounding corners conforming to the rounding corners of the frame, the sashes and the frame including the rounding corners, being formed with interfitting ribs and grooves, a retaining member extending entirely around the 25 window frame, and including a leg portion interposed between the frame and the wall of the window opening and a head portion having flanges lapping the body structure around the window opening and the window frame on the 30 side of the structure opposite that on which the first-mentioned flange is located, and fastening members extending through the bottom of the channel of the window frame, the leg member and into the body.

2. In a window construction, the combination 35 with a body formed with a rectangular window opening, of a rectangular window frame mounted in the opening formed with rounding corners, sashes slidably mounted in the frame and having 40 rounding corners fitting the rounding corners of the frame, the sashes and the frame, including the rounding corners, being formed with interfitting ribs and grooves, the portion of the frame along one rail thereof between the rounding corners at the ends of the rail and the interfitting parts thereon being removable as a unit, whereby when the sashes are moved out of engagement with the rounding corners within the 45 ends of the removable portion the sashes and the removable portion are demountable, as a unit, 50 from the frame.

3. In a window construction, the combination with a body formed with a rectangular window opening, of a rectangular window frame mounted in the opening and formed with rounding corners, 55 sashes slidably in the frame and having rounding corners fitting the rounding corners of the frame, the sashes and the frame, including the rounding corners, being formed with interfitting ribs and grooves, the frame including a removable section located between two of the rounding corners and along which both of the sashes are slidably, said section having parts interfitting with the sash and forming continuations of the interfitting parts at the rounding corners.

4. In a window construction, the combination with a body formed with a rectangular window opening, of a rectangular window frame mounted in the opening and formed with rounding corners, sashes slidably mounted in the frame and having 70 rounding corners fitting the rounding corners of the frame, the sashes and the frame, including the rounding corners, being formed with interfitting means, the frame including a base strip extending between two of the rounding corners 75

and a removable section overlying the base strip and along which both sashes are slideable, the removable section having means for interfitting with the sash, forming continuations of the interfitting means at the rounding corners.

5. In a window construction, the combination with a body formed with a window opening, of a window frame mounted in the opening, sash means mounted in the frame, the sash means 10 and the frame being formed with interfitting parts, the frame having an external flange lapping one side of the body around the window opening, and the frame including a removable section between two of the corners of the frame, 15 said section being formed with the parts thereof interfitting with the sash, forming continuations of the interfitting parts of the remainder of the frame and said section having an outwardly extending flange forming a continuation of the 20 former flange.

6. In a window construction, the combination with a body formed with a window opening, of a window frame mounted in the opening, sash means mounted in the frame, the sash means 25 and the frame being formed with interfitting parts, the frame having an external flange lapping one side of the body around the window opening, and the frame including a removable section between two of the corners of the frame, 30 said section being formed with the parts thereof interfitting with the sash, forming continuations of the interfitting parts of the remainder of the frame and said section having an outwardly extending flange forming a continuation of the 35 former flange, and fastening members extending through the frame into the body in a direction edgewise of the sash.

7. In a window construction, the combination with a body formed with a window opening, of a 40 window frame fitting in the opening and having an external circumferential flange lapping a face of the body around the window opening, a retaining member encircling the frame, and extending between the frame and the edge wall 45 of the window opening around the frame, the retaining member having a head at its outer edge lapping the side of the frame and the face of the body opposite to that on which the former flange is located, a sash in the frame, the portion 50 of the frame fitting into the opening being a flange and being provided with means directly thereon for receiving the sash, and fastening members extending through the frame, the retaining member and into the body in a direction 55 edgewise of the sash.

8. In a window construction, the combination with a body formed with a window opening, of a window frame fitting in the opening and having an external circumferential flange lapping the inner face of the body around the opening, a retaining member encircling the frame, and extending between the frame and the edge wall of the window opening around the frame, the retaining member having a head at its outer edge lapping the side of the frame and the side of the 60 body opposite to that on which the former flange is located, a sash in the frame and fastening members extending through the frame, the retaining member and into the body in a direction 65 edgewise of the sash, the frame and the sash 70 having interfitting tongue and groove means at the edges of the sash.

9. In a window construction, the combination with a body formed with a rectangular window opening, of a rectangular window frame mounted in the opening and formed with rounding corners, a pair of sashes slidably mounted in the frame 5 and having rounding corners fitting the rounding corners of the frame, the sash and the frame, including the rounding corners, being formed with interfitting ribs and grooves, respectively, the frame being channel-shaped in cross section 10 with the channel facing inwardly and the frame being formed with an external circumferential flange lapping one side of the body around the window opening, the frame also including a strip along one rail thereof between the rounding 15 corners, said portion being common to both sashes and having a flange forming a continuation of one of the side flanges of the channel, and a removable section on said strip and having a flange forming a continuation of said external 20 flange of the frame and also being formed with ribs for interfitting with the sash and forming continuations of the ribs at the rounding corners, a retaining member encircling the frame and 25 extending between the bottom of the channel and the body and between said strip and the body and having flanges overlapping the side flange of the channel and the face of the body opposite to that on which the first-mentioned flange is located and fastening members extending through 30 the bottom of the channel and into the body and the interposed retaining strip and the body and through the removable section, the base strip and interposed retaining member and the body.

10. In a window construction, the combination with a body formed with a window opening, of a window frame having a portion telescoping into the opening and a circumferential flange at an angle to the telescoping portion and lapping one lateral side face of the body around the opening, 40 a member having a portion complementary to the former frame portion and telescoping into the opening from the opposite side of the opening from that on which the frame is mounted and also lapping and lying flatwise on the telescoping portion of the frame, said member having an angular marginal flange lapping the other lateral side of the body around the window opening, the outermost lapping portion being provided with means directly thereon for receiving a sash, 45 and fastening members extending through the telescoping and lapping portions of the frame and said member and extending in a direction edgewise of the sash.

11. In a window construction, the combination with a body formed with a window opening; of a window frame including opposite sections, each having a body portion telescoping into the opening, the body portion telescoping into the opening and a circumferential flange at an angle to the telescoping portions, and the flanges of said sections lapping respectively the lateral side faces of the body around the opening, the telescoping portions of said sections lying flatwise on each other, and the outermost telescoping portion being formed with means for receiving the margin 60 of the sash, and fastening members extending through the telescoping portions in a direction edgewise of the sash and located in the plane of the sash.
